RAILWAY TRUCK DEVICE

Carl E. Tack, Chicago, Ill., assignor to General Steel Castings Corporation, Eddystone, Pa., a corporation of Delaware

Application May 20, 1940, Serial No. 336,172

8 Claims. (Cl. 105—190)

The invention relates to railway rolling stock, and more particularly to truck construction, and consists in all of the novel features hereinafter described and illustrated in the accompanying drawings.

Recent developments in the design of high-speed light-weight trains have utilized truck bolster springs of upright coils to provide more flexibility than has been common heretofore. Such bolster springs are likely to oscillate vertically and to yield laterally so freely as to detract from easy riding qualities. One of the objects of the present invention is to provide a yielding resistance for the lateral deflection of free-acting bolster springs, whether of the coil type or otherwise constructed.

In a common type of truck structure, the bolster is mounted for lateral movement in the truck frame by being carried on swing hangers pivoted to the truck frame and mounting the bolster springs. Another object of the invention is to transmit lateral forces from the bolster to the swing hangers through a yielding device to insure movement of the hangers on their pivots and to prevent undesirable rocking of the bolster on the bolster springs.

These and other detailed objects of the invention are attained by the structure illustrated in the accompanying drawings in which—

Figure 1 is a top view of the central portion of a four-wheeled truck including a lateral motion bolster, part of which is broken away for the purpose of clearly illustrating the parts beneath.

Figure 2 is a vertical transverse section taken on the line 2—2 of Figure 1.

Figures 3 and 4 are detail vertical sections extending longitudinally of the truck and taken on the corresponding section lines of Figure 2.

Figure 5 is a detail horizontal section through the bolster and spring plank connecting device and is taken upon section line 5—5 of Figure 2.

Figure 6 is a detail vertical section taken on the line 6—6 of Figure 5.

Figure 7 is a vertical transverse section corresponding to Figure 2 but illustrating another form of the invention.

Figure 8 is a detail top view and horizontal section taken on the line 8—8 of Figure 7.

Figures 9 and 10 are detail vertical transverse sections taken on the corresponding section lines of Figure 7.

The truck illustrated in Figures 1 to 6 includes a truck frame carried by wheeled axles in the usual manner and having wheel pieces 1 and transoms 2, the frame supporting springs being 55

indicated at 3, spring carrying equalizers being indicated at 4, and the truck wheels being indicated at 5. Suspended from the frame by pivot pins 6 are swing hangers 7, the hangers at each side of the truck being connected by cross bars 8 which support the ends of a spring plank 9 extending from side to side of the truck. Each end of the spring plank seats one or more upright coil springs 10 which support the truck bolster 11 extending from side to side of the truck and including center plate structure 12 on which the vehicle body (not shown) is mounted in the usual manner.

The spring plank is provided with a recess or opening 13 extending longitudinally of the spring plank and transversely of the truck. A vertical rib 14 extends from side to side of this opening near one end thereof and a bracket 15 depends from the bottom of bolster 11 at a point spaced transversely of the truck a substantial distance from rib 14.

A bolster and spring plank anchoring device has its opposite ends secured to rib 14 and bracket 15. This device is detailed in Figure 5 and includes a rod 16 telescopingly received in a tube 17. Rubber bushings 18 and 19 connect the rod to the tube. Preferably, each rubber bushing is bonded to inner and outer sleeves 20 and 21, respectively, which are welded at W to rod 16 and tube 17, respectively. The right hand end of rod 16 has a collar 22, fixed to the rod as by welding at W', and a movable collar 23 secured by a nut 24. Rubber discs 25 are arranged at opposite sides of the depending bracket flange 15a and are clamped against the flange by the tightening of nut 24.

The opposite end of tube 17 carries a fixed collar 26 and a movable collar 27, and rubber discs 28 are clamped between collars 26 and 27 and a spring plank rib 14. The clamping nut 29 is threaded upon a stud 30 secured in tube 17.

Preferably, the opposing faces of each pair of discs and the metal part clamped between them are of concavo-convex contour and preferably a rubber ring 31 surrounds the rod or tube where it passes through the metal rib 14 and bracket flange 15a thereby preventing metal to metal contact between the spring plank and bolster through the anchoring device. Preferably, bolster bracket 15 is made separately from the bolster and is bolted thereto to facilitate the application of the anchoring device, although this bracket may be made integral with the bolster if desired.

With the anchoring device applied, bolster

springs 10 may function to yieldingly support the bolster. Although their departure from a normal height would be accompanied by some resistance from the anchoring device, the latter may yield by the distortion of discs 25 under the leverage provided by the length of rod 16 and tube 17 between elements 14 and 15. The resistance of disc 25 to such distortion will tend to dampen the action of bolster springs 10.

Forces tending to move the bolster laterally of the truck will be transmitted to the spring plank and the lower ends of the swing hangers mainly through the anchoring device, rather than through the bolster springs, the inertia of the swing hangers and their load being overcome by the resistance to shear in rubber bushings 18, 19 and, to a lesser degree, by the resistance to distortion in rubber discs 25, 28. The pivotal movement of the swing hangers will avoid tilting of the bolster springs and excessive lateral movement of the bolster without corresponding movement of the swing hangers. Hence, the device may supplement or take the place of vertically disposed shock absorbers at the side of the truck connected to the bolster and truck frame.

The invention contemplates an anchorage from the bolster to the swing hanger supported structure and this anchorage does not depend upon the presence or use of the spring plank as described above. Figures 7-10 illustrate another form of the invention in which a pair of anchoring devices 40 are secured to flanges 41, integral with and depending from the bolster 42, and to flanges 43, depending from the spring seats 44 mounted on the cross bars 45 carried by the swing hangers 46 suspended at 47 from the truck frame transoms 48.

The individual anchorage devices 40 correspond in structure, attachment and function to the devices previously described although somewhat shorter and duplicated at opposite sides of the truck center line. The rubber elements of devices 40 will be of the proper resilience to maintain the lower portions of the swing hanger structures in proper transverse spaced relation. Spring seats 44 have arcuate bearings 49 on cross bars 45, and this permits the spring seats to remain horizontal throughout swinging movement of hangers 46. If desired, the anchorage devices could be connected directly to cross bars 45 by providing a suitable pivotal or yielding joint between them.

The details of the anchor structure and the connections to the bolster and to the bolster spring carrying parts may be varied substantially from the illustrated forms without departing from the spirit of the invention and the exclusive use of such modifications as come within the scope of the claims is contemplated.

What is claimed is:

1. In a railway truck, a frame, a bolster, bolster carrying structure arranged to move laterally of said frame and including upright coil springs supporting said bolster, an elongated device extending transversely of the truck with one end yieldingly secured to said bolster only and with the other end yieldingly secured to said structure only, whereby said bolster and structure may move vertically relative to each other due to the action of said springs, the ends of said device being movable towards and from each other, and said device including means yieldingly resisting such movements whereby a force tending to move said bolster transversely of the truck relative to said structure will be transmitted from said

bolster to said structure independently of said springs.

2. In a railway truck, a bolster, supporting springs therefor, a spring plank for carrying said springs, said bolster and spring plank each having a vertically disposed web, said webs being spaced apart transversely of the truck, and an anchorage device extending between said webs and comprising telescoping members, means yieldingly resisting the telescoping movement of said members, the outer member having a pair of rubber discs and elements for clamping one of said webs between said discs and the inner member having a pair of rubber discs and means for clamping the other of said webs between the latter-mentioned discs.

3. A railway bolster anchorage device comprising a tube member, a rod member received therein, a rubber bushing surrounding said rod member with its inner and outer surfaces secured to said rod member and tube member respectively, means for connecting one end of one of said members to a truck bolster and means for connecting the other end of the other of said members to another truck part, the means for connecting one member end to an associated truck part including rubber elements to cushion forces transmitted between said truck part and said device laterally of the truck and to dampen vertical oscillations of said truck part relative to other truck parts.

4. A railway bolster anchorage device comprising an elongated tube member, a rod member therein extending substantially the length of the tube member and projecting therefrom at one end, a relatively short rubber bushing near each end of the tube and rod members with its inner and outer surfaces secured to the rod member and tube member respectively, means for connecting one end of one of said members to a truck bolster, and means for connecting the other end of the other of said members to another truck part.

5. A railway bolster anchorage device as described in claim 4 in which the means for connecting one member end to an associated truck part comprises a pair of radial collars with opposing rubber discs and elements for clamping the truck part between the discs.

6. A railway bolster anchorage device as described in claim 4 in which the means for connecting one end of the device to an associated truck part comprises a pair of radially disposed rubber discs mounted on the rod member, and elements for clamping the truck part between said discs, and in which the means for connecting the other end of the device to an associated truck part comprises a pair of radially disposed rubber discs mounted on the tube member, and elements for clamping the corresponding truck part between said latter-mentioned discs.

7. A railway bolster anchorage device comprising a tube member, a rod member received therein, a rubber bushing surrounding said rod member with its inner and outer surfaces secured to said rod member and tube member respectively, means for connecting one end of one of said members to a truck bolster and means for connecting the other end of the other of said members to another truck part, the means for connecting one member end to an associated truck part comprising a pair of radial collars with opposing rubber discs and elements for clamping the truck part between the discs.

8. In a railway truck, a frame, swing hangers pivotally suspended therefrom, springs carried by

said hangers, a bolster supported on said springs, a device extending transversely of the truck and comprising separate parts each having one end anchored to said bolster and hanger respectively, there being rubber elements connecting said parts and placed in shear by relative movement of said parts transversely of the truck whereby

lateral transverse forces may be yieldingly transmitted from said bolster through said device to the lower portions of said hangers to effect cushioned movement of said hangers with said bolster laterally of the truck.

CARL E. TACK.
